DESIGN FOR A COSTUME JEWELRY PIN

John Caianiello, New York, N. Y.

Application October 3, 1945, Serial No. 122,501

Term of patent 3½ years

(Cl. D45—19)

To all whom it may concern:

Be it known that I, John Caianiello, a citizen of the United States, residing at 940 Broadway, in the county of New York and State of New York, have invented a new, original, and ornamental Design for Costume Jewelry Pins, of which the following is a specification, reference being had to the accompanying drawing, forming part thereof.

I claim:

The ornamental design for a costume jewelry pin, as shown.

JOHN CAIANIELLO.
